UNITED STATES PATENT OFFICE

GARRETT W. MUDD, OF CHICAGO, ILLINOIS, ASSIGNOR, BY MESNE ASSIGNMENTS, TO CHICAGO CURLLED HAIR COMPANY, OF CHICAGO, ILLINOIS, A CORPORATION OF ILLINOIS

METHOD OF PRODUCING AN UPHOLSTERY PAD

Application filed April 17, 1929. Serial No. 355,782.

Heretofore pads of this character have usually been formed by providing a body portion of hair or other material to which a fabric cover has been attached; and to form piping other material has been secured to the face of the pad in a manner to produce tubular casings extending across the pad.

These tubular casings are then filled by inserting the hair or filling thereinto by means of an implement suitable for the purpose.

The process is not only laborious but necessitates considerable time and is somewhat expensive.

15 The pads thus formed are then covered with a desired material, such as leather, fabric or other material, and then incorporated in the furniture or seat with which it is to be used.

20 It is one of the objects of the present invention to provide an improved pad of this character and method of producing the same, which will not only possess all of the attributes of the old form of pad, but the cost of manufacture of the same will be materially reduced.

25 A further object is to provide an improved pad of this character in which the filling of the pad will be shaped to the desired form and the covering material secured thereto during the forming operation of the body portion thereof, thereby dispensing with the necessity of inserting any additional filling after the casing or covering is in place.

30 A further object is to provide an improved pad of this character in which the casing for the padding material and the final covering may, if desired, be simultaneously secured to the pad, thereby reducing to a minimum the number of steps in the operation of producing the pad.

35 To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a top plan view of a pad of this character constructed in accordance with the principles of this invention.

Figure 2 is an enlarged detail sectional transverse view of the body portion of the 55 pad.

Figure 3 is an enlarged detail sectional view taken on line 3—3, Figure 1.

Figure 4 is a view similar to Figure 3, of 60 another form of pad.

Figure 5 is a view similar to Figures 3 and 4, showing the pad partially formed, and another means of attaching the covering.

Figure 6 is an enlarged detail sectional 65 view of one of the pad sections.

In carrying out this invention the pad proper is preferably formed of a backing 10 such as burlap or any other suitable material, to which the body portion 11 of the pad is secured in any suitable manner such as by 70 what is known as an interlacing operation, that is by drawing portions of the material forming the body portion 11, through the backing 10, as at 12.

75 During the forming of the body portion of the pad, the material 11 is arranged or shaped so as to produce channels 13 which extend entirely across the pad and open through one face thereof. The channels 13 80 may be of any desired width and the portions 11 which will, by the formation of the channels 13, assume the shape of strips, may be of any desired thickness and width.

85 After the body portion has thus been formed it is covered by any suitable material 14 such as cotton batting or any other material of any desired thickness. Over this covering 14 may be placed another covering 15 of any suitable fabric. These two coverings 14 and 15 may be secured in position 90 at the same time or separately if desired, and in securing them to the body portions of the materials 14 and 15 are bent back upon themselves and the bent back portions are inserted 95 respectively in the channels 13 after which the portions of the materials within the channels are secured to the backing 10 in any desired or suitable manner by means of fastening devices 16, preferably in the form of stitching. The operation of drawing the 100

folded portion of the cover into the channels 13 will serve to shape the portions 11 of the pad which constitute the filling now used in pads of this character and forming the 5 piping.

If desired, when the covering material 14 and 15 have thus been secured in position the pad in its completed form will be ready for use, but before the same is placed in position 10 upon the seat, furniture or other place where it is to be used, it is usually customary to provide another or finishing cover for the pad, such as a cover 17 of flexible material.

If the coverings 14 and 15 are already secured in position, then the covering 17 is bent back upon itself at spaced intervals as at 18 and inserted in the channels 13 or into the pockets or recesses formed by the folded portions of the material 14 and 15. The covering 17 is then secured in position by means 20 of stitching 19 or may be fastened in any desired or suitable manner.

If desired the covering 17 may be secured in position at the same time that the coverings 14 and 15 are secured to the pad. In that event the three coverings 14, 15 and 17 are superposed and laid upon the pad in a manner to extend thereacross. Then the folded portions designated generally by the 30 reference numeral 20 in Figure 5, are inserted into the channels 13 and fastened with stitching 21, or in any desired or suitable manner.

As shown at the right hand end of Figure 35 5, the materials 14, 15 and 17 may be secured in position in another manner and to that end the covers 15 and 17 may be bent back upon themselves as indicated generally by the reference numeral 22 and stitching 23 may 40 be made through the bent back portion so that when the portion of the cover is then bent forwardly to cover another section 11 of the body as shown at 24 in Figure 5, the stitching 23 will be covered.

With this improved construction of pad, it will be manifest that the pads may be supplied to the customer or user with or without the final covering and it will also be manifest that with this improved construction 50 and process the forming of the usual piping casings and the insertion of the filling into the casings after the casings have been formed, will be obviated, with the result that the amount of labor necessary to produce the 55 pad will be materially reduced, as well as the cost of manufacture.

Obviously the coverings may be secured to the pad in any suitable manner, either simultaneously or separately.

While the preferred form of the invention has been herein shown and described, it is to be understood that various changes may be made in the details of construction and in the combination and arrangement of 60 the several parts, within the scope of the

claim, without departing from the spirit of this invention.

What is claimed as new is:—

The method of forming pads for upholstering and the like which consists in securing filling material of considerable thickness to a flexible backing and forming isolated portions of the material to produce channels therebetween extending across the pad open at their tops and closed at their bottoms by the said flexible backing, then applying a flexible covering for said portions of filling material, said covering extending across said channels, then drawing portions of the covering material into the channels and securing the same to the said flexible backing at the bottom of the channels.

In testimony whereof I have signed my name to this specification, on this 28th day of March, A. D. 1929.
